UNITED STATES PATENT OFFICE.

WILLIAM SCHAAKE, OF PITTSBURGH, PENNSYLVANIA, ASSIGNOR TO WESTINGHOUSE ELECTRIC AND MANUFACTURING COMPANY, A CORPORATION OF PENNSYLVANIA.

TROLLEY.

1,241,558.

Specification of Letters Patent.

Patented Oct. 2, 1917.

Application filed April 12, 1915. Serial No. 20,644.

To all whom it may concern:

Be it known that I, WILLIAM SCHAAKE, a citizen of the United States, and a resident of Pittsburgh, in the county of Allegheny 5 and State of Pennsylvania, have invented a new and useful Improvement in Trolleys, of which the following is a specification.

My invention relates to trolleys, and it has special reference to pantograph trolleys 10 that are respectively adapted to collect relatively large amounts of current from trolley conductors when operating at high speeds.

One of the objects of my invention is to provide a structure of the above indicated 15 character which shall be simple, light and durable in construction and which shall embody an arrangement of parts that shall relieve the pantograph frame of unnecessary frictional resistance, particularly while it 20 is being lowered in position by means of fluid-actuated operating devices.

In pantograph trolleys, as usually constructed, the fluid-actuated operating devices are commonly supported in the central 25 longitudinal plane of the pantograph frame and frequently are carried directly upon the transverse operating shafts, or, at least, are connected thereto at substantially their midpoints. Therefore, there is a tendency, when 30 performing their intended functions, to spring the shafts out of alinement. It has been found advisable, therefore, to provide suitable bearing members at the central portions of the shafts, as well as at their ends, 35 in order to maintain the positions thereof and prevent undue strains therein.

With such a construction, however, the force of the fluid-actuated operating device, that normally tends to spring the shaft, is 40 taken up by the central bearing member, and, therefore, a considerable amount of frictional resistance is encountered which renders the operation of the pantograph frame relatively sluggish and unresponsive. 45 Moreover, it is difficult to aline three bearing members, and, consequently, undesirable friction is practically certain.

According to my present invention, I propose to overcome these difficulties and to 50 provide a pantograph trolley in which the fluid-actuated operating devices are supported directly by a suitable supporting frame at the sides of the pantograph frame proper, instead of in the middle thereof, and it is

my intention to associate said operating devices with the transverse shafts near the ends thereof and adjacent to the end bearing members, whereby the usual central bearing members may be omitted and the strains which tend to spring the shafts are 55 avoided.

Moreover, as a consequence of this arrangement of parts, a material reduction in the frictional resistance of the pantograph frame is realized which renders the structure 60 particularly responsive to varying operating conditions and insures good electrical contact and smooth running qualities.

In the accompanying drawings, Figure 1 is a view, partially in section and partially 65 in side elevation, of a pantograph trolley constructed in accordance with my invention, and Fig. 2 is a plan view of the apparatus shown in Fig. 1, certain parts of the apparatus being broken away in both figures 70 for the sake of clearness and economy of space.

Referring to the drawings, the apparatus shown comprises a plurality of supporting 75 insulators 1, a supporting frame structure 2 carried thereby, a pantograph frame 3 mounted upon said structure, a current-collecting device 4 associated with said pantograph frame, an interconnecting mechanism 5 for prescribing the movements of the pantograph frame, a plurality of fluid-actuated 80 operating devices 6 for lowering the pantograph frame, and a plurality of springs 7 for elevating said frame.

The supporting insulators 1 are disposed 85 longitudinally, in pairs, on the respective sides of the device and are severally provided with caps 10 having integral oppositely projecting lateral lugs 11 upon which a pair of longitudinally disposed supporting 90 members or angle irons 12 are positioned. The supporting members 12 constitute a part of the frame structure 2, the other portion thereof comprising transverse supporting members or angle irons 100 13 which are rigidly fastened to the longitudinal supporting members 12 and also a centrally disposed longitudinal supporting member or angle iron 14 which is rigidly associated with the transverse supporting 105 members 13, in a suitable manner. Supporting members 15 also form parts of the frame structure 2, being secured between

the respective pairs of longitudinal members 12 for the purpose of supporting the operating devices 6.

5 Rotatable operating shafts 17 are disposed transversely in parallel relation and are rotatably mounted, at their respective ends, in bearing members 19 that are secured beneath the inner supporting members or angle irons 12. The shafts 17, 10 however, project beyond the bearing members 19, at one end and on the opposite sides of the apparatus, whereby the shaft extensions are conveniently located with reference to the corresponding operating devices 6 by means of which the shafts may 15 be actuated in a manner to be hereinafter set forth.

The pantograph frame 3 comprises a plurality of jointed frame-members 22 and 23 20 the upper ends of which are pivotally united together in a suitable manner and support the current-collecting device or contact shoe 4 and the lower ends thereof are severally fixed to the rotatable shafts 17.

25 Inasmuch as my present invention has no direct bearing upon the specific structural details of the pantograph frame, it is deemed sufficient to state that any well-known and applicable type of construction 30 may be employed, a detailed description of a suitable structure being presented in a co-pending application, Serial No. 20,680, filed by Christian Aalborg of even date herewith and assigned to the Westinghouse 35 Electric & Manufacturing Company, to which reference may be made.

Reference may, however, be had to the lower frame members 25 of the pantograph structure which are secured to the operating shafts 17 and which severally embody a toothed cam 26 and a downwardly projecting arm 27. Intermediate the cams 26 of the lower frame members 25 that are located on the corresponding sides of the apparatus, is the coil elevating spring 7 which has its respective ends connected to chains 28 that engage the toothed cams 26 in the usual manner and serves to actuate the pantograph frame to its raised position.

50 The interconnecting linkage 5 comprises a bell-crank lever 31 that is pivoted upon a shaft 32 which is suitably supported beneath the supporting members or irons 12. The respective ends of the bell-crank lever 31 are associated with the downwardly projecting arms 27 of the adjacent lower frame members 25 by means of links 33 and 34, whereby the linkage serves as an equalizer between the component jointed frame-members 22 and 23 of the pantograph frame 3 and, moreover, serves to insure vertical movements thereof.

The operating cylinders or fluid-actuated devices 6 are of like construction and each 65 is mounted upon the supporting members

or angle irons 13 and 15 which constitute parts of the supporting frame structure 2, and, each comprises a cylinder 36, a movable piston 37 contained therein and a crank arm 38 having a roller 39 disposed at one 70 end and in engagement with the piston 37, the other end thereof being rigidly secured to the transverse shaft 17. Thus, when operating fluid is admitted to one end of the cylinder 36, the piston 37 is actuated and rotates the transverse operating shaft 17 through the agency of the crank arm 38 and thereby causes the pantograph frame 3 to be lowered.

The crank arm 38 is fixed to the extended portion of the operating shaft 17 and adjacent to the bearing member 19, whereby the effort exerted by the operating mechanism is delivered to the shaft in proximity to its bearing members and, hence, there 85 is little tendency to cause the shaft to spring. Moreover, by this arrangement of parts a minimum number of bearing members is provided and, hence, all unnecessary frictional resistance is eliminated.

I contemplate various changes in the construction of the apparatus shown and described, and, in order that I may protect such changes as do not depart from the spirit and scope of my invention, I desire 95 that only such limitations shall be imposed as are indicated in the appended claims.

I claim as my invention:

1. In a trolley, the combination with a supporting frame, a plurality of transverse 100 rotatable shafts, bearing members for supporting the ends of said shafts upon said frame, and a pantograph frame mounted upon said shafts and adapted to be raised into its operative position, of means disposed at the side of said pantograph frame and coöperating with said shafts for lowering said pantograph frame.

2. In a trolley, the combination with a supporting frame, a plurality of transverse 110 rotatable shafts carried thereby, a pantograph frame mounted upon said shafts, and means coöperating therewith for elevating said frame, of means disposed on the respective sides of said pantograph frame and 115 severally coöperating with said respective shafts for lowering said pantograph frame.

3. In a trolley, the combination with a supporting frame, a plurality of transverse 120 rotatable shafts, and a pantograph frame mounted upon said shafts, of a plurality of fluid-actuated devices carried by said supporting frame and severally associated with the respective shafts and disposed on the opposite sides of said pantograph frame for 125 actuating said frame.

4. In a trolley, the combination with a substantially square supporting structure, and a pantograph frame mounted thereon and adapted to be raised and lowered in po- 130

sition, of means mounted upon diametrically opposite corners of said supporting structure for actuating the said pantograph frame to only a lowered position.

5 5. In a trolley, the combination with a supporting structure, and a pantograph frame mounted thereon and adapted to be raised and lowered in position, of a plurality of actuating means independently carried by said supporting structure and respectively disposed at diametrically opposite corners of the pantograph frame, said actuating means adapted to operate only for lowering said frame.

10

15 6. In a trolley, the combination with a supporting structure, a plurality of transverse operating shafts, a plurality of bearing members for rotatably associating the respective ends of said shafts with said supporting structure, and a pantograph frame mounted upon said transverse shafts and adapted to be raised and lowered in position, of means associated with said operating shafts adjacent to the supporting bearing members for raising said pantograph frame, and means also associated with said shafts adjacent to the bearing members for lowering said pantograph frame.

7. In a trolley, the combination with a supporting structure, a plurality of transverse operating shafts, a plurality of bearing members for rotatably associating the respective ends of said shafts with said supporting structure, and a pantograph frame 30 mounted upon said transverse shafts and adapted to be raised and lowered in position, of a plurality of coil springs disposed at the respective sides of said pantograph frame and coöperating with said operating 35 shafts near their respective ends for elevating said pantograph frame, and a plurality of fluid-actuated operating devices disposed at the respective sides of the pantograph frame and severally mechanically 40 associated with one end of the respective operating shafts adjacent to the bearing 45 members.

8. In a trolley, the combination with a

plurality of supporting insulators, caps attached to said insulators and having oppositely projecting lateral arms, supporting members disposed on the respective sides of said insulators and carried by said supporting arms, and a pantograph frame pivotally supported between said side supporting members and adapted to be raised and lowered in position, of a plurality of fluid-actuated devices disposed on the respective sides of said pantograph frame and carried by said side supporting members and mechanically associated with said pantograph frame for actuating the same. 50 55 60

9. In a trolley, the combination with a supporting structure, a plurality of transverse shafts, a plurality of bearings disposed near the ends of said shafts for rotatably mounting the same upon said structure, a pantograph frame rigidly mounted upon the shafts and adapted to be raised and lowered in position, and a plurality of coil springs interposed between the shafts and operatively connected thereto for biasing the same to a raised position, of fluid-operated means disposed substantially near the ends of said shafts for lowering the said frame. 65 70 75

10. In a trolley, the combination with a substantially square supporting structure, a plurality of transverse shafts, means for operatively connecting the corresponding ends of the shafts, a pantograph frame rigidly mounted upon the shafts and adapted to be raised and lowered in position, and a plurality of coil springs interposed between the shafts near the ends thereof and co-operating therewith for biasing said frame to an operative position, of means for lowering said frame respectively disposed at diametrically opposite corners of said supporting structure and operatively connected to the shafts substantially near the ends thereof. 80 85 90

In testimony whereof, I have hereunto
subscribed my name this 30th day of March
1915.

WILLIAM SCHAAKE.
